(57) **CLAIM**

The ornamental design for a charger for camera battery, as shown and described.

DESCRIPTION

FIG. 1 is a front, left side, top perspective view of a charger for camera battery showing my new design;

FIG. 2 is a rear, left side, bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right end elevational view thereof; and,

FIG. 8 is a left end elevational view thereof.

The broken lines immediately adjacent to the claimed portions are boundaries, all other broken lines are environmental structures; all the broken lines form no part of the claimed design.
